UNITED STATES PATENT OFFICE.

FERDINAND NIES, THEODOR VOGEL, AND FRITZ BERG, OF MANNHEIM-ON-THE-RHINE, GERMANY.

DEVICE FOR SEPARATING LIQUIDS FROM GAS OR THE LIKE.

1,159,073.

Specification of Letters Patent.

Patented Nov. 2, 1915.

Application filed December 1, 1911. Serial No. 663,449.

To all whom it may concern:

Be it known that we, FERDINAND NIES, THEODOR VOGEL, and FRITZ BERG, subjects of the Grand Duke of Baden, in the German Empire, and residents of Mannheim-on-the-Rhine, Dukedom of Baden, Germany, have invented certain new and useful Improvements in Devices for Separating Liquids from Gas or the like, of which the following is a specification.

The invention relates to improvements in devices for separating liquids from gases or vapors and especially in separating oil from the exhaust steam from steam engines.

The object of the invention is to improve the operation of such devices, to reduce the cost of the apparatus and more especially to divide the steam into separate narrow currents of the greatest possible uniformity.

The invention has also for its object to generally improve the construction of such apparatus to render it more capable of performing its required duties.

In order that the invention may be fairly understood the same is described with reference to the accompanying drawings which illustrate one modification thereof.

In these drawings Figure 1 is a cross section through one part of the device which is herein described as the bar element. Fig. 1^a shows a modified construction of the bar element in cross-section. Fig. 2 is a side view of the bar element shown in Fig. 1. Fig. 3 is a view corresponding to Fig. 2 of a bar element with a different arrangement of openings. Fig. 4 is a general arrangement showing a number of elements in cross section. Fig. 5 is a cross section of a device for separating oil with the arrangement of bar elements shown in Fig. 4. Fig. 6 is a side view of several of the elements shown in Fig. 1 associated to form a bundle of elements. Fig. 7 is a side view of the bundle of elements shown in Fig. 6 looking in the direction of the arrow *x*. Fig. 8 is a detailed view of the bundle of elements shown in Fig. 6. Fig. 9 is a cross section through a general arrangement of a large number of bundles of elements associated to form a ribbed structure. Fig. 10 is a detail of the ribbed structure shown in Fig. 9.

In the following description similar parts are designated by similar reference letters.

The arrangement according to Figs. 1 to 5 will first be described.

The ribbed or bar element shown in Fig. 1 is provided according to this invention with a cross section in the shape of three-arms meeting at a point. *a a¹ a²* are sections of the bars which are preferably formed of a single strip of sheet metal, although it is also possible to construct the elements from two strips connected at the arm *a²*, by means of rivets, screws or any other suitable means as shown in Fig. 1^a. In Fig. 1 the elements are shown as made of one single strip. The arms *a a¹*, are provided with a large number of round holes *a³*. In the form according to Fig. 3 the holes are of elongated rectangular shape. The rod according to Fig. 1^a consists of two strips of metal sheets, which are riveted together at *a²*.

According to the present invention the elements shown in Fig. 1 are associated or assembled in the manner shown in Fig. 4. As shown in Fig. 4 the perforated arms *a a¹*, form the sides of rhomboids, while the unperforated arms *a²*, form a diagonal of these rhomboids. There is no fastening device employed for fastening the elements to one another. All the elements are surrounded at their upper and lower ends by a holding frame *b b¹ b² b³*. These holding frames are arranged in a casing *c*, which is provided with two pipe connections *c¹ c²*. Below the lower frame is arranged within the casing a perforated bottom (not particularly illustrated), supporting the elements or bars at their lower ends, whereas the cover of the casing is arranged in close proximity to their upper ends. The frames (*b¹ b² b³ b⁴*) may be fastened to the casing in any suitable manner, as shown in Fig. 5, angle iron bars *a⁴* are used, the one leg of which is screwed or riveted to the frame and the other to the casing. Steam, from which the oil is to be separated, may enter at *c¹*, pass through the casing in the direction of the arrow *x*, and leave the device by the outlet *c²*.

The elements are so arranged in the frame that they are supported with their free ends or edges *a⁴ a⁵*, against the side *b* of the frame. The elements of the next row of bars are supported against the edges *a⁶* and *a⁷*. The bar elements of the next previous

row rest against the corners a^6 and a^7 . The previous row of any two rows is that which is first met by the steam passing in the direction of the arrow x . With this structure any displacement of the bar elements in the direction of the flow of the steam is prevented by the free ends a^8 , of the arms a^2 , which abut against the bottom a^9 , of the groove formed by the arms a^1 . In the longitudinal direction displacement is prevented by the arms of the elements resting against the perforated bottom of the casing c , and at the same time the elements are supported at their upper ends against the cover.

The method of operation is easily understandable. Steam, entering in the direction of the arrow x , is first divided into streams by the diagonals a^2 . The steam must then pass through the perforated and inclined arms a^1 . The oil contained in the steam is in this way separated and flows downwardly, and is taken off from the container in the known manner. The purified steam then passes by the outlet c^2 , from the separator casing.

It is preferable to support the last row of bars against a strip b^4 , Fig. 5, instead of directly against the holding arms b . In this case by tightening up the screws the strip b^4 , may be raised to compress the bar elements together to form a firm structure.

A further object of the present invention is to associate the separate bar elements into so-called bundles of elements outside the casing, and then to assemble the bundles of elements so as to form a bar structure. For this purpose the arms a^2 , are provided with projections a^{10} . e are metal bars which bind these projecting ends together. All the elements are then fastened to the binding bars or strips by means of rivets a^{11} . In this way a so-called bundle of elements is provided as shown in Figs. 6 and 7. These bundles of elements are then assembled in the frame in the manner shown in Fig. 9. It may be advisable to fix the ends e^2 , of the bars or strips e , in toothed walls f , fastened to the frame so as to prevent any side movement of the bundle of elements and also to fix absolutely the correct position of all the bundles in relation to one another. With this structure the steam is divided and subdivided in a very uniform manner.

It is not necessary to rivet all the bar elements to the holding strips. It is sufficient to fasten only the two ends of the first and last elements, whilst the remaining elements hold each other mutually with their edges a^8 , against the base a^9 . It is also immaterial for the present invention what means are employed for fastening the bar elements together, so as to form a bundle of elements. It is only of importance that the separate bars, as for instance, shown in Fig. 1, are

united to form a bundle of elements, and that these are again associated in turn to form an entire bar structure in order that the series of bars arranged in an exact manner in parallel arrangement is assured. It is also immaterial to the present invention what form the holes a^3 , take, and in what manner they are made. In the form shown in Fig. 7 the material is pressed out so that projections or points remain at the edges of the holes.

What we claim is:

1. In an apparatus for separating liquids from gas and the like a number of separating bars of Y-section with two perforated and one unperforated section the latter having the direction of the flow of the gas the rods being assembled to mutually support each other, each single bar being supported by the adjacent bars at its longitudinal edges and at the section line of the three sections and a casing having a steam inlet and outlet and adapted to receive and support the said separating bars.

2. In an apparatus for separating liquids from gas and the like a number of separating bars of Y-section with two perforated and one unperforated section the latter having the direction of the flow of the gas, each bar consisting of two strips of sheet metal riveted together and being supported by the adjacent bars at its longitudinal edges and at the section line of the three bar sections and a casing having a steam inlet and outlet and adapted to receive and support the said separating bars.

3. An apparatus for separating liquids from gases comprising in combination a casing having a steam inlet and a steam outlet, a number of separating bars of Y-section with two perforated and one unperforated section the bars being assembled to mutually support each other, each single bar being supported by the adjacent bars at its longitudinal edges and at the section line of the three bar sections, holding frames surrounding the bars at their upper and lower ends and means for fastening the said frames to the said casing.

4. An apparatus for separating liquids from gases comprising in combination a casing having a steam inlet and a steam outlet, a number of separating bars of Y-section with two perforated and one unperforated section the bars being assembled to mutually support each other, each single bar being supported by the adjacent bars at its longitudinal edges and at the section line of the three bar sections, holding frames surrounding the bars at their upper and lower ends, means for fastening the said frames to the said casing and a compressing device consisting of two strips, supporting against the last row of bars, screws arranged in the adjacent frame strips of the holding

frames and supporting against the first-mentioned strips.

5. In an apparatus for separating liquids from gases and the like, a number of bundles of separating elements, each bundle consisting of several bars or rods of Y-section having two perforated and one unperforated section the rods supporting each other at the free edges of the unperforated 10 sections, metallic strips arranged at the upper and lower ends of the rods, means for

fixing the rods to the said strips and means for supporting the said strips within the casing.

In witness whereof we have hereunto set 15 our hands in the presence of two witnesses.

FERDINAND NIES.

THEODOR VOGEL.

FRITZ BERG.
